UNITED STATES PATENT OFFICE.

ALBERT A. GORDON, OF WORCESTER, MASSACHUSETTS, ASSIGNEE TO CROMPTON & KNOWLES LOOM WORKS, OF WORCESTER, MASSACHUSETTS, A CORPORATION OF MASSACHUSETTS.

CHAIN FOR LOOM PATTERN MECHANISM.

Application filed April 18, 1927. Serial No. 184,642.

This invention relates to improvements in pattern chains for looms and the method of their manufacture and it is the general object of the invention to provide an improved chain the links of which shall be uniform and more durable than those heretofore provided.

In fancy or shuttle box looms it is necessary to provide some means to determine the sequence in which the various shuttles become active and it is common practice to employ a so-called pattern chain which operates on one or more box mechanism controlling levers. The chain may be given either a constant or intermittent movement and ordinarily comprises both high and low links, a change from one to the other of these types of links effecting a movement of the lever which controls the box motion. It is necessary that the chain link shall have a relatively broad surface to bear against the control lever and it is furthermore necessary that the links be so formed that they can be hooked together to form a continuous chain. As a matter of fact the chain links shown herein are used more particularly on so-called multipliers, although they can be used on the main part of the box chain.

Heretofore chain links of the type set forth herein have been molded and made of cast iron but they are so small that the handling, snagging and drilling operations render them relatively expensive considering their weight. It is an important object of my present invention to provide a substitute for the cast iron link, said substitute being formed of sheet metal pressed to a proper shape and being provided with wings which are bent into alignment around a connecting portion which subsequently forms the bearing for the control lever.

It is a further object of my invention to provide an improved method by means of which the links are made.

With these and other objects in view which will appear as the description proceeds, my invention resides in the combination and arrangement of parts hereinafter described and set forth in the claims.

In the accompanying drawings wherein one form of my invention is shown,

Fig. 1 is a side elevation of a portion of a pattern mechanism for a box loom having my improved chain applied thereto,

Fig. 2 is a plan view of one of the blanks from which a chain link is formed,

Figs. 3, 4 and 5 represent successive steps in the forming of the chain link,

Fig. 6 is a side elevation of the chain link when the same is in the form shown in Fig. 5 and looking in the direction of arrow 6 of that figure,

Fig. 7 illustrates the manner of aligning the wings of the link,

Fig. 8 is a top plan view of a short section of the chain formed according to my present invention, and

Fig. 9 is a view similar to Fig. 7 but showing a low link.

Referring to Fig. 1 it will be seen that I have illustrated my chain in connection with a multiplier such as is commonly employed with all cylinder motions for gingham looms and for dobby multipliers. A stationary shaft 10 has mounted thereon a sprocket 11 which is rigid with a ratchet wheel 12. A stud 13 affords pivotal mounting for a lever 14 which is given a periodic oscillation about said stud by mechanism not shown but well understood. A pull pawl 15 is pivoted to the lever 14 as at 16 and provided for actuating the ratchet wheel 12. Said pawl has a shield 17 which receives the end thrust of a rod 18 carried by a control lever 19. The latter is pivoted on a fixed stud 20 and has a spring arm 21 connected to a tension spring 22 and has also a chain engaging arm 23 having a shoe 24 to be raised by the chain to be described.

The pawl 15 is shown in operative position with respect to the ratchet 12, being permitted to assume this position by reason of the fact that the shoe 24 is resting on a low link of pattern chain 25. The rod 18 is thus moved to the left by spring 22 and shield 17 follows it. For a further understanding of a device similar to that already described, reference may be had to my prior Patent Number 1,060,977.

It is to be understood that the matter set forth in Fig. 1 is merely illustrative and that my invention can be applied to any one of a number of chain operated mechanisms which may differ from that shown in Figure 1.

My invention relates more particularly to chain links and the method of their manufacture and I have illustrated the successive

steps in making these links in the drawings from Figs. 2 to 7. I first provide a blank 50 having two pairs of wings, one pair lying to the right and the other pair to the left of the vertical line passing through the center of the blank the upper member of each pair being indicated at 51 and the lower member being indicated at 52. Each wing is perforated as at 53 and there is left between the wings 51 and 52 on each side of the blank a recess 54 to receive one of the teeth of the sprocket 11 after the link is formed. The connecting bearing portion 55 between the links 51 is defined at the lower end thereof as seen in Fig. 2 by the upper end of a recess 56 which separates the wings 52 and is formed as a ceratoid cusp the curved sides of which are eventually aligned to cooperate with the control lever. Extending from the upper end of the part 55 is a tongue 57 the purpose of which is to provide extra bearing surface for the control lever.

The second step in forming the link is illustrated in Figs. 3 and 4 where it will be seen that the wings 51 have been offset from the wings 52 as shown clearly in Fig. 4. As shown in Figs. 2 and 3 the offsets indicated at 58 are in line with the apex of the recess 56 and for this reason the wings 52 will bend independently of wings 51 and without distorting the latter. The reason for the offset is apparent from Fig. 8. During this step the tongue 57 may be curved downwardly slightly, as indicated in Fig. 4.

35 In the third step the blank shown in Fig. 4 and indicated in dotted lines in Fig. 5 is subjected to a bending operation which leaves the connecting bearing portion 55 as indicated in Fig. 5, but bends the wings from 40 the dotted line position down to the full line position.

The fourth and last step in forming the link consists in simultaneously pressing together the sides shown as flaring in Fig. 5 and at the same time acting on the wings to align the perforations 53 in pairs. This step is shown in Fig. 7 where it will be seen that the lower tool or holder 60 is provided with a tongue 61 which extends into the recesses 54 and this figure also illustrates the upper tool 62 as having a concave face 63 which engages the upper edges of the link to move the same to proper alignment as the members 60 and 62 are made to approach each other.

50 As shown in Figs. 6, 7 and 8 the portion 55 which forms the connection between the several wings is of sufficient breadth and length to afford proper bearing for the shoe 24 of lever 23. The bearing for the shoe 24 is further enlarged by the tongue 57, and as the latter is depressed in the offsetting step prior to the bending, said tongue serves to space the wings 51. The width of tongue 57 is slightly greater than twice the thickness 60 of the steel stock so that the wings 52 on

one link can fit between the spaced wings 51 on the adjacent link. It will further be seen that as the perforations 53 are formed in the blanking out or first operation it is unnecessary to subject the chain link to the drilling 70 operations such as are necessary with the ordinary cast iron link. I find that the chain links described herein are cheaper than the cast iron links heretofore used and are more uniform and provide a bearing for the lever 75 23 which is substantially equal in effectiveness to that of the cast iron link.

From the foregoing it will be seen that I have provided a link for loom pattern chain mechanisms formed of pressed metal having 80 wings bent around the central body of the blank in such a way as to provide a bearing surface for the shoe. It will further be seen that the recess 56 extending to bearing portion 55 permits ready offsetting of the wings 52 from the wings 51, the point of offset of the wings 52 as indicated in Fig. 3 being substantially at the upper end of the recess 56 so that as the wings on the opposite sides are bent as indicated in Fig. 5 the connecting portion 55 may be left of sufficient width to space the wings 51. Furthermore, the tongue 57 adds bearing surface for the lever and also acts to space the wings 51. The bending operations are facilitated by the fact 95 that the apex of recess 56 is substantially in line with the apices of recesses 54.

Having thus described my invention it will be seen that changes and modifications may be made therein by those skilled in the art 100 without departing from the spirit and scope of the invention and I do not wish to be limited to the details herein disclosed, but what I claim is:

1. A link for loom pattern mechanism 105 chains, said link being formed of a single piece of sheet metal and having two pairs of wings parallel to each other, the members of one pair being in contact with each other and the members of the other pair being spaced from each other, and said link having a portion to which all the wings are secured forming a bearing surface for a pattern chain lever.

2. A link for loom pattern mechanism 115 chains, said link being formed of a single piece of sheet metal and having two pairs of wings parallel to each other, the members of one pair being in contact with each other and the members of the other pair being 120 spaced from each other, said link having a bearing portion to which all the wings are secured to form a bearing surface for a pattern chain lever, and a tongue projecting from the body of the bearing portion and lying between the spaced members of said other pair of wings to separate the same and forming an extension of the bearing portion of the link.

3. A link for loom pattern mechanism 130

chains, said link being formed of a single piece of sheet metal and having two pairs of wings all lying in different but parallel planes, the members of one pair lying closely adjacent to each other and the members of the other pair being separated, and said link having a connecting portion to which all of said wings are attached, said connecting portion being substantially perpendicular to the planes of the wings to present a bearing surface for a bearing chain lever.

4. A link for loom pattern mechanism chains, said link being formed of a piece of sheet metal and having two pairs of wings which are parallel to each other, the members of one pair being pressed closely together and the members of the other pair being separated a distance approximately the same as the thickness of the two members which are closely adjacent to each other, said link having a connecting portion for all the wings to which the latter are attached, said connecting portion presenting the bearing for a pattern lever and lying principally between the members of the separated pair of wings.

5. A link for loom pattern mechanism chains, said link being formed of a single piece of sheet metal and having two pairs of wings, the members of one pair lying closely adjacent each other and the members of the other pair being offset from the planes of the wings which are closely adjacent each other, said link having a connecting portion to which all of the wings are secured, said connecting portion presenting a bearing surface for a pattern mechanism lever and said bearing portion lying to one side of the offset between the pairs of wings.

6. A blank for a loom pattern chain link, said blank being formed of sheet metal and having two pairs of wings and a connecting portion, said wings and connecting portion being integral, said connecting portion lying between the members of one pair and that portion of the blank lying between the members of the other pair being cut away.

7. A blank for a loom pattern chain link, said blank being formed of sheet metal and having two pairs of wings and a connecting portion, said wings and connecting portion being integral, said connecting portion lying between the members of one pair and that

portion of the blank lying between the members of the other pair being cut away, the members of the second named pair being offset with respect to the members of the first named pair, said pairs lying in substantially parallel planes.

8. A blank for a loom pattern chain link, said blank being formed of sheet metal and having two pairs of wings and a connecting portion, said wings and connecting portion being integral, said connecting portion lying between the members of one pair and that portion of the blank lying between the members of the other pair being cut away, the members of one pair of wings being offset from the members of the other pair, and the connecting portion lying to one side of the offset.

9. That process in a forming of loom pattern chain links which consists in the following steps, providing a blank having two pairs of wings, the members of the first pair being separated by a blank space and the members of the second pair being joined together by a bearing portion, offsetting the wings of the first pair out of the plane of the wings of the second pair, and bending said wings so that the offset members of the first pair lie closely adjacent each other and the members of the second pair are separated by the bearing portion.

10. The process of forming pattern chain links which consists in the following steps; providing a blank having two pairs of wings with a connecting portion between the members of one pair of wings and with the portion of the blank between the members of the other pair removed, offsetting the members of one pair out of the plane of the other pair of wings, providing a tongue to extend from the connecting portion between the members of the first named pair of wings, bending said tongue in a direction from the first named pair of wings toward the plane of the second named pair of wings, and folding the blank so that the members of the second named pair lie close together and the members of the first named pair are separated and spaced by the tongue.

In testimony whereof I have hereunto affixed my signature.

ALBERT A. GORDON.
